DESIGN FOR A LAMP

John F. Kirby, Lakewood, Ohio, assignor to National Plastics, Inc., Cleveland, Ohio, a corporation of Ohio

Application July 26, 1939, Serial No. 86,253

Term of patent 3½ years

To all whom it may concern:

Be it known that I, John F. Kirby, a citizen of the United States and resident of Lakewood,
in the county of Cuyahoga and State of Ohio,
have invented a new, original, and ornamental Design for a Lamp, of which the following is a specification, reference being had to the accompanying drawing, forming a part thereof.

In said drawing, Fig. 1 is a front elevational view of a lamp showing my new design; Fig. 2 is a side view; Fig. 3 is a top plan view; and Fig.
4 is a rear view.

I claim:

The ornamental design for a lamp, as shown.

JOHN F. KIRBY.
